[57] **CLAIM**

The new and ornamental design for a security anchor for securing a portable article against theft, as shown and described.

DESCRIPTION

FIG. 1 is a perspective view of a security anchor showing my design;

FIG. 2 is a top plan view thereof;

FIG. 3 is a right elevation thereof;

FIG. 4 is a left elevation thereof; and,

FIG. 5 is a front elevation thereof, the rear elevation being the same as the front elevation.

The bottom of the security anchor is plain and unornamented.
